FURNACE CHARGING MACHINE

Harvey W. Ball, Alliance, Ohio, assignor to The
Morgan Engineering Company, Alliance, Ohio,
a corporation of Ohio

Application July 7, 1948, Serial No. 37,483

10 Claims. (Cl. 214—18)

1

This invention pertains to furnace charging machines, and more particularly to apparatus of the type using a rockable and rotatable peel in feeding open-hearth furnaces, and distributing charging stock in the hearths of such furnaces.

The primary object of the invention is to provide a machine for this purpose, so designed that no projecting parts of the machine will interfere with the operator's line of vision to the charging box at the end of the peel, or to either side of the cabin of the trolley. This will result in greater safety to persons in the vicinity of the machine, and minimize damage to the machine and other objects in the adjacent vicinity thereof.

A further object is the provision of a charging machine in which the trolley is driven along the bridge by means spaced transversely of the trolley, so as not to interfere with up and down movements of the peel; the driving means for the trolley being positioned about midway between the front and rear ends thereof, and functioning also to stabilize the trolley.

Another object is to supply a charging machine having a trolley mounted on a bridge in such manner as to prevent shocks to the operator. In other words, I provide the trolley with novel shock absorbing means, and in my construction, the fulcrum point or axis, for the up and down movement of the peel, is so positioned, as to produce nearly a perfect balanced condition of the peel assembly. Thus, the charge in the charging box is the only unbalanced load to be counteracted by the shock absorbing springs or the like.

With the foregoing and other objects in view, it will be apparent as the description proceeds, that the invention resides in the combination and arrangement of parts, and in the details of construction, hereinafter described and claimed, it being understood that changes in the precise embodiment of the invention herein disclosed, may be made within the scope of what is claimed, without departing from the spirit of the invention.

In the accompanying drawings:

Fig. 1 is a perspective view of a charging machine, in accordance with the invention, such machine being shown mounted on floor tracks, adjacent to parallel tracks, for the cars which transport the charging boxes.

Fig. 2 is a diagrammatic top plan view of the trolley and a portion of the peel.

Fig. 3 is an enlarged side elevation, partly in longitudinal vertical section, and partially broken away, of the shock absorbing means at one side of the rear end of the trolley.

2

Fig. 4 is a transverse vertical sectional view, taken on the line 4—4 of Fig. 3.

Fig. 5 is a view similar to Fig. 4 of a portion of the mechanism with the peel unloaded.

Referring to the drawings, 10 designates horizontal tracks or rails on the floor of the building or the like, containing a battery of open-hearth furnaces (not shown). Between the tracks 10 and the furnaces (as is customary), rails 11 are arranged on the floor parallel to the rails 10, for the travel of cars (not shown), supporting charging boxes 12, one of which is illustrated in Fig. 1. Each charging box is adapted to be connected to the head of a peel 13, preferably of the type disclosed in my application, Serial No. 30,601, filed June 2, 1948. In that application, I have shown and described means for rigidly securing one end of a charging box to the outer end or head of the peel, and means for rotating the peel so that the charging box may be dumped after it has entered the furnace.

In accordance with the present invention, a bridge 14, including spaced parallel girders 15, form part of a carriage, having wheels (not shown) that the travel along the rails 10. The girders are connected together at opposite ends of the carriage, and at the front end of the carriage, a guard apron 16 is fixed, and provided with a notch 17, to accommodate movements of the peel 13. The opposite ends of the girders are operatively and fixedly connected by an overhead frame 18, of such height as to permit the cabin 19 of a trolley 20, to move beneath the horizontal portion of the framework, when necessary.

The bridge 14 may be propelled along the tracks 10, by any suitable means, now used in the art.

In keeping with the present invention, the trolley has a body 21, arranged entirely below the windows 22 at the front and sides of the cabin 19, and no parts of the mechanism of the trolley extend above the top of the body. Hence, the operator, within the cabin can readily observe conditions at both sides thereof, as well as look forward toward the head of the peel and the charging box 12, without having his vision obstructed. To facilitate nonobstruction of the operator's vision, the top of the body 21, forwardly of the front window of the cabin, slopes forwardly and downwardly, as indicated at 23, toward the front end 24 of the trolley. Said front end has depending ears 25, supporting a horizontal pin or shaft 26, carrying the cradle 27 of the peel. The latter rocks about the axis of the pin 26, and its rear end may be moved upwardly and downwardly under the control of the operator,

by any suitable means 28, diagrammatically illustrated in Fig. 2.

At this point, it will be observed that the trolley is provided at its sides, with oppositely projecting shelves or platforms 29, which move with the trolley along the girders 15. Each shelf supports a reversible electric motor 30 having a shaft 31, driving a reduction gearing 32. As illustrated in Fig. 2, each of said reduction gearings has a horizontal shaft 33, extending through a side 34 of the trolley, and driving a wheel 35, journalled in suitable bearings 36, and travelling on one of the rails 37 at the tops of the girders 15. Obviously, when the motors are energized, they rotate the wheels 35 and propel the trolley along the rails 37, so as to project the peel 13 beyond the shield 16 or withdraw it into a position entirely between the girders 15 of the bridge.

It may be clearly seen from Fig. 2 that the two shafts 33 are spaced from one another transversely of the trolley, and, therefore, the space between the wheels 35 is not obstructed by any crosswise shaft that would interfere with the up and down movements of the portion of the peel within the chassis of the trolley.

The wheels 35 constitute the front wheels of the trolley, and the rear wheels thereof are indicated at 38. Each wheel 38 is journalled in the rear end 39 of the trolley, and is not only arranged to absorb shocks, but cooperates with another shock absorbing wheel 40 (Figs. 3 and 4), engageable with an inverted rail 41, depending from, and fixed to, a girder 15.

Referring to Figs. 3 and 4, it will be observed that each wheel 38 of the trolley, is mounted in anti-friction bearings 42, arranged within a truck member 43 that spans the wheel and has shock absorbing cups 44, positioned at its corners, forwardly and rearwardly of the axis 45 of the wheel 38. Each cup has a wear plate 45a, vertically 40 slidable on a wear plate 46, fixed to a wall 47, forming part of the chassis of the trolley.

For yieldingly urging the wheels 38 downwardly onto the tracks 37 of the bridge, legs 48 have their upper ends connected by transverse horizontal pivot pins 49 to fixed parts 50 of the trolley chassis. An inverted cup or socket 51 slides in each cup 44 and has its upper end in threaded engagement (52) with a sleeve 53, loosely surrounding a pin 54, constituting a portion of leg 48. The latter has an abutment 55 against which the upper end of the inverted cup 51 bears. Friction type coil springs 56 of the kind commonly used in railway draft mechanism, and which creates friction under a predetermined pressure, surround the sleeve 53, and bear at one end against the top of the inverted cup 51, and at the other end against shoulders within a sleeve 51, and at the exterior of the sleeve 53. At this point, it will be obvious that the springs 56 can be adjusted by turning the inverted cup 51.

Each sleeve 57 has an external flange 58 at its upper end, bearing upon a coil spring 59, seated in the cup 44. As the abutment 55 is engageable with the top of the inverted cup 51, and the sleeve 53 can move downwardly with said cup, it is obvious that the friction springs 56 will act upon the sleeve 57 to compress the springs 59 after the springs 56 are compressed a predetermined degree. In other words, it will be clear from Fig. 3, that as the legs 48 move downwardly, while the wheels 38 are in engagement with the tracks 37, springs 56 and 59 will function, respectively, to snub the movement and absorb shocks resulting therefrom.

A nut 60 and a lock nut 61 has threaded engagement with the lower end of each pin 54, to maintain the parts in assembled relation and prevent the pins 54 from pulling upwardly out of the truck member 43.

It will be understood from Figs. 3 and 4, that I preferably employ two cups 44 at each side of each wheel 38, and there are two of these cups arranged fore and aft of each wheel. Of course, 10 there are also four of each of the parts with which the cups co-operate.

As further illustrated in Figs. 3 and 4, the chassis of the trolley below and in vertical alignment with the vertical diameter of each wheel 15 38, is provided with a rockable bearing sleeve 62, designed to rock laterally of the trolley and limited in rocking, by any suitable means, such as a pin 63, fixed to the chassis, and projecting into a groove 64 in the periphery of the bearing sleeve 62. The latter houses an anti-friction bearing 65, in which is journalled one end 66 of the shaft 67 of one of the wheels 40, and while only one ensemble is illustrated in Figs. 3 and 4, it will be understood that the lower wheel 40 at 20 each side of the trolley is carried in the same way. Each wheel 40 is fixed to an end 68 of the shaft 67, opposite the end 66, and the intermediate portion of each shaft 67 is journalled in an anti-friction bearing 69, mounted in a transversely rockable ring 70, having a parti-spherical 30 periphery 71, slidable laterally in a complementary seat of a collar 72, which has a pin 73, extending into a groove 74 of the ring, and serving the same purpose as the parts 63 and 64.

As shown in Fig. 3, the collar 72 is provided with fore and aft extending arms 75, each terminating at an inverted cup 76. Each of these cups slidably engages a vertical wear plate 77, rigidly united with a depending part or wall 78 of the trolley chassis. Rods 79 depend from, and are pivotally supported by, a horizontal shaft 80, which extends fore and aft of the trolley and is reinforced by gussets 81, constituting parts of the chassis. Sleeves 82 are slidably arranged on the rods and the movement of the sleeves in one direction is limited by nuts 83, 84, having threaded engagement with the lower ends of the rods. A cup 85 has threaded engagement (86) with the lower end of each sleeve, and the upper end portion of each sleeve is provided with an external shoulder to bear against friction springs 87 of the type above-mentioned. The lower ends of these springs bear against the inner faces of the bottoms of the cups 85. Other sleeves 88 are slidably arranged within the inverted cups 76 and have shoulders at their upper ends bearing against the upper ends of the springs 87. Coil springs 89 surround portions of the sleeves 88, and bear at their upper ends against the internal 55 surfaces at the upper ends of the inverted cups 76, and at their lower ends against external flanges 90 at the lower ends of the sleeves 88.

Each spring structure 86, 87 may be of the conventional helical type so arranged that the springs are normally under a partial compression in order to exert a pressure on the track wheels on the rails. Therefore, any force, tending to tilt the trolley on the bridge, is resisted by preloaded springs.

Referring to Fig. 4, it will be noted that if the peel is not loaded by a charging box and its contents, the end 68 of the shaft 67 would be higher than the end 66 (Fig. 5). In other words, each shaft 67 would incline downwardly toward 70 its end 66, and the rings 72, 76 would be canted

so that the right hand walls (Fig. 5) of the grooves 64, 74 would be closer to the pins 63, 13, than would the left hand walls of the grooves. At such time, the rear end 39 of the trolley would be slightly lower than its front end. When, however, the peel picks up a charging box and its load, the rear end of the trolley will "kick-up" slightly, so that the shafts 67 will assume approximately horizontal positions under the usual load, as shown in Fig. 4.

It will be evident from Figs. 2 and 4, that the axles of the wheels 38 and 40 at each side of the trolley, are spaced from the similar wheels at the opposite side thereof. In other words, there is no axle extending entirely across the trolley at the rear thereof which would interfere with vertical movements of the peel, peel cradle, or the peel operating means.

In the operation of the machine, it will be obvious that the carriage or bridge 14 may be propelled along its tracks 10 to a position in front of any one of a battery of open-hearth furnaces, and as charging box supporting cars will be on the rails 11, the trolley may be propelled forwardly on the girdles 15, by means of the motors 30, to bring the head of the peel 13 into position to engage a charging box in alignment with the particular furnace being served. At this time, the peel will be moved about the fulcrum 26 to cause its head to engage the charging box. Now the trolley may be moved further forwardly by the motors 30 to introduce the charging box and its load into the furnace, after which the peel can be rotated to dump the contents of the box into the furnace. Subsequently, the peel can be rotated to place the charging box top-side-up, and then the motors 30 can be reversed to cause the peel to carry the charging box back to the position over a car travelling on tracks 11. Afterwards, the peel can be released from the charging box, and be retracted into the carriage 14, by causing the motors 30 to propel the trolley 20 rearwardly further along the tracks 31. During such operation, it is obvious that the operator's view through the front window of the cabin 19, is not obstructed, and he can readily see everything forwardly of the trolley. Furthermore, when the trolley and peel are in retracted position, the operator, in shifting the carriage from one side to the other, along rails 10, may readily observe conditions at either side of the trolley, as will be evident from an inspection of Fig. 1.

During operation of the peel, the shock absorbing mechanism, shown in Figs. 3 and 4, will come into play, and shocks caused by movement of the outer end of the peel and its load, will not be imparted to the trolley cabin or the operator.

While I have disclosed what I deem to be a preferred form of the apparatus, I do not wish to be limited to the details thereof, as there may obviously be changes made in the form, construction and arrangement of the constituent elements as well as their modus operandi, without departing from the spirit of the invention as comprehended within the scope of the appended claims.

What I claim is:

1. In a furnace charging machine of the type having a horizontally movable carriage, a trolley movable horizontally on the carriage at right angles to movement of the carriage, front and rear wheels supporting the trolley on the carriage, and a peel having an intermediate por-

tion fulcrumed to the front end portion of the trolley for movement about a horizontal axis arranged transversely of the trolley, the improvement in which the trolley is provided with shock absorbing means yieldingly urging the rear wheels of the trolley toward the carriage, the latter having inverted rails, the trolley also having shafts positioned below its rear wheels and fulcrumed to the trolley for movement about horizontal axes extending lengthwise of the trolley, wheels movable about the axes of said shafts and engaging the inverted rails, and other shock absorbing means operatively associated with said shafts for yieldingly urging the last-mentioned wheels into constant contact with the inverted rails.

2. In a furnace charging machine of the type having a horizontally movable carriage, a trolley movable horizontally on the carriage at substantially right angles to movement of the carriage, front and rear wheels supporting the trolley on the carriage, and a peel supported by the carriage, the improvement in which the trolley is provided with shock absorbing means yieldingly urging the rear wheels of the trolley toward the carriage, the latter having inverted rails, the trolley also having shafts positioned below its rear wheels and fulcrumed to the trolley for movement about horizontal axes extending lengthwise of the trolley, wheels movable about the axes of said shafts and engaging the inverted rails, and other shock absorbing means operatively associated with said shafts for yieldingly urging the last mentioned wheels into constant contact with the inverted rails.

3. In a furnace charging machine of the type having top upright rails and bottom inverted rails, a trolley movable lengthwise of said rails, front and rear wheels supporting the trolley on the top rails, and a peel supported by the trolley, the improvement in which the trolley has shafts positioned below its rear wheels and fulcrumed to the trolley for movement about horizontal axes extending lengthwise thereof, wheels movable about the axes of said shafts and engaging the inverted rails, and shock absorbing means operatively associated with said shafts for yieldingly urging the last mentioned wheels into constant contact with the inverted rails.

4. In a furnace charging machine of the type having top upright rails and bottom inverted rails, a trolley movable lengthwise of said rails, front and rear wheels engaging the top rails and supporting the trolley thereon, and a peel supported by the trolley, the improvement in which the trolley has substantially aligned transverse shafts, the outer ends of which are fulcrumed to the trolley for movement about horizontal axes extending lengthwise thereof, wheels movable about the axes of said shafts and engaging the inverted rails, and shock absorbing means operatively associated with said shafts for yieldingly urging the last mentioned wheels into constant contact with the inverted rails.

5. In a furnace charging machine of the type having a plurality of upright rails and a plurality of inverted rails, a trolley movable lengthwise of said rails, front and rear wheels supporting the trolley on the top rails, and a peel carried by the trolley, the improvement in which the trolley has oppositely disposed shafts fulcrumed to the trolley for movement about parallel horizontal axes extending lengthwise of the trolley, wheels movable about the axes of said shafts, and engaging the inverted rails, and shock absorbing

means operatively associated with said shafts for yieldingly urging the last mentioned wheels into constant contact with the inverted rails.

6. In a furnace charging machine of the type having a plurality of upright rails and a plurality of inverted rails, a trolley movable lengthwise of said rails, front and rear wheels supporting the trolley on the top rails, and a peel carried by the trolley, the improvement in which the trolley has oppositely disposed shafts fulcrumed to the trolley for movement about parallel horizontal axes extending lengthwise of the trolley, wheels movable about the axes of said shafts, and engaging the inverted rails, and shock absorbing means operatively associated with each of said shafts for yieldingly urging the last mentioned wheels into contact with the inverted rails, the shock absorbing means including spring structures normally under a partial compression.

7. In a furnace charging machine of the type having a pair of upright parallel rails and a pair of inverted parallel rails, a trolley movable horizontally lengthwise of said rails, front and rear wheels supporting the trolley on the upright rails, and a peel carried by the trolley, the improvement in which the trolley is provided with stub shafts spaced apart and projecting toward one another, the outer ends of the shafts being fulcrumed to the trolley for movement about parallel horizontal axes extending lengthwise of the trolley, wheels movable about the axes of said shafts and engaging the inverted rails, said wheels being mounted on the inner ends of said shafts, and shock absorbing means operatively connected with intermediate portions of said shafts for yieldingly urging the last mentioned wheels into contact with the inverted rails.

8. In a furnace charging machine, a pair of parallel upright rails, a pair of parallel inverted rails, means operatively connecting said rails for maintaining them in fixed positions relatively to one another, a horizontally movable trolley, front and rear wheels supporting the trolley on the upright rails, and a peel carried by the trolley, the improvement in which the trolley is provided with shock absorbing means yieldingly urging the rear wheels of the trolley toward the upright rails, the trolley also having, at opposite sides thereof, a pair of shafts positioned below the rear wheels, and having outer end portions fulcrumed to the trolley for movement about horizontal axes extending lengthwise of the tracks, other wheels movable about the axes of said shafts and engaging the inverted rails, and other shock absorbing means operatively associated with said shafts for yieldingly urging the last mentioned wheels into constant contact with the inverted rails.

9. In a furnace charging machine of the type

having a horizontally movable carriage, a trolley movable on the carriage at right angles to the movement of the carriage, front and rear wheels supporting the trolley on the carriage, and a peel fulcrumed to the trolley for movement about a horizontal axis arranged transversely of the trolley, the improvement in which the trolley is provided with shock absorbing means yieldingly urging the rear wheels of the trolley toward the carriage, the latter having inverted rails at the opposite sides thereof, the trolley also having substantially aligned transverse shafts at the opposite sides thereof, positioned below the rear wheels, and fulcrumed to the trolley for movement about horizontal axes arranged substantially parallel to the inverted rails, wheels movable about the axes of said shafts and engaging the inverted rails, and other shock absorbing means operatively associated with said shafts for yieldingly urging the last mentioned wheels into constant contact with the inverted rails.

10. In a furnace charging machine of the type having a horizontally movable carriage, a trolley movable horizontally on the carriage at right angles to movement of the carriage, front and rear wheels supporting the trolley on the carriage, and a peel fulcrumed to the trolley for movement about a horizontal axis arranged transversely of the trolley, the improvement in which the peel is movable upwardly and downwardly between the front wheels and between the rear wheels, and the trolley is provided with shock absorbing means yieldingly urging the rear wheels toward the carriage, the latter having inverted rails, the trolley also having a pair of transverse shafts positioned below the rear wheels and having outer end portions fulcrumed to the trolley for movement about horizontal axes extending lengthwise thereof, wheels mounted on the other ends of the shafts, movable about the axes of the shafts and engaging the inverted rails, and other shock absorbing means operatively associated with the medial portions of said shafts for yieldingly urging the last mentioned wheels into contact with the inverted rails.
